United States Patent Office.

CURTIS R. STICKNEY, OF HARTFORD, CONNECTICUT.

Letters Patent No. 65,445, dated June 4, 1867

MATCH-BOX AND CANDLESTICK COMBINED.

The Schedule referred to in these Letters Patent and making part of the same.

TO ALL WHOM IT MAY CONCERN:

Be it known that I, CURTIS R. STICKNEY, of Hartford, in the county of Hartford, and State of Connecticut, have invented a new and improved Match-Box and Candlestick Combined; and I do hereby declare that the following is a full, clear, and exact description of the construction and operation thereof, reference being had to the accompanying drawings, and to the letters of reference marked thereon.

Figure 1 shows a side view of the improved match-box and candlestick combined.

Figure 2 shows a top view of the same.

Figure 3 shows a vertical section through the middle.

Figure 4 shows a horizontal section on the line *m n*.

Like letters in the several figures indicate like parts.

My invention consists in combining a match-box and a self-acting candlestick in a portable form, suitable to be carried in the pocket. Also in the arrangement of the parts of the candlestick, and giving to the cover of the candle-tube a form proper to receive and protect the wick of the enclosed candle.

A is the tube or case forming the match-box, which is supplied with a cover of ordinary construction, with a hinge at *a*, and secured when closed by a snap at *b*. *B* is the candle-tube, which is constructed as follows: *d* is the outside shell, to which is attached the match-tube, and to which the cover *D* is attached by the hinge *a*, and which also has a snap at *c* for securing the cover when closed. *e* is an inside tube, which slides into the tube *d* from the top. It is shown in the drawings of the same length as the tube *d*, and is held in place by its friction on *d*, or by a projection on its lower edge catching into a groove upon the inside of the tube *d*. At the top the tube *e* has a lip turned over on the inside to retain the candle *C*, and prevent its being pushed out by the spiral spring *s*, provided with a cap, *f*, which continually presses it upward. The cover *D* is rounded up in the middle so as to form a receptacle for the wick when the cover is closed, preserving it in a suitable condition for relighting. The candle *C* is pushed up by the spring *s* as it is consumed, so that the top is always at the same height. When it is desired to replace the candle, the tube *e* is removed by inserting some convenient instrument under the lip at the top and drawing it upward out of the tube *d*, when a new candle can be inserted and the tube replaced. The roughened surface *E* on the outside of the case is placed upon one of the tubes of the outside case in such a manner, as shown in the drawings, that the other tube serves as a guide for the match passed along its surface and prevents it from slipping off.

What I claim as my invention, and desire to secure by Letters Patent, is—

1. I claim the combination of a match-box and self-acting candlestick when formed of two parallel tubes substantially as herein set forth.
2. I claim the combination of the tube *e* with the outside shell *d*, and the cover *D*, substantially as herein described and for the purpose set forth.
3. I claim the cover *D*, having a receptacle for the wick of the candle, substantially as herein described.
4. I claim the placing of the roughened surface *E* in such a position that one of the tubes shall serve as a guide for the match when passed over its surface, substantially as herein described.

CURTIS R. STICKNEY.
